(57) **CLAIM**

The ornamental design for a welding helmet with adjustable fans, as shown and described.

DESCRIPTION

FIG. 1 is a front perspective view of a welding helmet with adjustable fans with the fans in a forward position showing my new design;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a back view thereof; and,

FIG. 8 is a left side view thereof, with the fans in an up position and two fans illustrated in broken lines in a mid-position and a downward position.

The broken lines in FIG. 8 illustrate alternative positions of the adjustable fan and are not part of the claimed design.
